Cyrus A. Anderson

ATTORNEY.

UNITED STATES PATENT OFFICE.

KARL MUHLEISEN, OF PHILADELPHIA, PENNSYLVANIA, ASSIGNOR TO SCHUTTE AND KOERTING COMPANY, OF PHILADELPHIA, PENNSYLVANIA, A CORPORATION OF PENNSYLVANIA.

HEAT-EXCHANGE APPARATUS.

Application filed December 4, 1922. Serial No. 604,669.

To all whom it may concern:

Be it known that I, KARL MUHLEISEN, a citizen of the United States, and a resident of Philadelphia, in the county of Philadelphia and State of Pennsylvania, have invented an Improvement in Heat-Exchange Apparatus, of which the following is a specification.

My invention relates broadly to heat exchange apparatus and more particularly to the means for connecting or securing a header to the tube-plate or sheet, the edge of which forms an expansion joint with the adjacent portion of the casing of such apparatus.

One object of the invention is to provide a novel construction of means whereby a header may be detachably connected with a tube-plate or sheet only slightly larger in diameter than the outside diameter of the bundle of tubes or pipes to which the said plate or sheet is secured and still leave sufficient clearance to permit the removal of a defective tube or pipe and the substitution of another therefor after the header is removed.

A further object is to provide an improved construction of means for retaining packing in position around a tube-plate or sheet and a flange projecting outwardly therefrom for the purpose of sealing the joint between such sheet and the exterior casing of the apparatus.

To these and other ends my invention comprehends the construction and arrangement of parts as hereinafter fully described, particularly pointed out in the claims and as illustrated in the drawing forming a part of this specification. It is to be understood, however, that my invention is susceptible of embodiment in other forms of construction than that shown and that changes in the details thereof may be made within the scope of the claims without departing from the same.

In the drawings:

Fig. 1 is a central longitudinal sectional view of a portion of a heat exchange apparatus provided with my invention; and Fig. 2 is a transverse sectional view taken on the line 2—2 of Fig. 1.

Referring to the drawing: 1 designates a casing from which extends a tubular projection 2 which has a flange 3 to which the

end of a conduit (not shown) is adapted to be secured. The oil or other fluid to be cooled enters the casing by way of the opening through the tubular projection 2 and escapes from a corresponding outlet opening (in known manner) adjacent the opposite end of the casing.

Situated within the casing 1 are pipes or tubes 5 to which are secured baffle-plates 6 arranged as shown which operate to cause the oil or other fluid which may enter through the tubular projection 2 to flow in a zigzag direction through the casing 1 and about the pipes 5. The ends of the pipes or tubes 5 are secured within openings in a tube-plate or sheet 8 in any known manner, which plate or sheet is adapted to move within the casing 1 due to the expansion and contraction of said pipes. It will be understood that the opposite ends of these pipes or tubes are also secured in a tube-plate or sheet secured or fastened to the opposite end of the casing 1 in any desired known manner.

The tube-plate or sheet 8 is provided with a forwardly extending flange 9 the forward edge of which is provided with an inwardly extending narrow flange 10. The tube-plate is situated within the end of the casing 1 and fits the same closely, as indicated at 12. The end portion of the casing 1 which extends beyond the tube-plate 8 is provided upon the innerside with a recess 15 which extends entirely around the same, which recess surrounds the outer portion of the edge of the tube-plate 8 and also surrounds the flange 9 previously referred to. Packing material 16 is situated within the said recess around the edge portion of the tube-plate 12 and also around a portion of the flange 9. For the purpose of compressing the packing material 16 tightly within the recess 15 so as to hold it closely against a portion of the outer edge of the tube-plate 8 and a portion of the outer surface of the flange 9 and the inner surface of the recess 15 I have provided a gland 17 having an outwardly extending flange 18 which is parallel with a flange 19 which extends outwardly from the adjacent end of the casing 1. The flange 19 is provided with screw-threaded openings 20 at intervals therein in which screw-threaded bolts 21 are secured. The outer ends of these bolts project through

100

105

openings 22 in the flange 18. For the purpose of forcing the gland inwardly against the packing 16 nuts 23 are screwed on to the outer ends of the screw-threaded bolts 5 21 against the flange 18 to thereby force the gland 17 inwardly against the packing 16.

For the purpose of securing the header 25 to the forward edge portion of the flange 9 I have provided the inner end portion of 10 the said header with a flange 26, the outer inner edge portion of which is provided with a recess 27 which extends entirely around the same. The forward edge of the flange 9 projects into the said recess and a 15 washer-like ring 30 of suitable material is interposed between the edge of said flange and the bottom of the recess 27 for the purpose of effecting a water and steam tight joint between the flanges 9 and 26. The inner edge of the washer-like ring member is seated against a shoulder at the inner edge of the recess 27 and the edge portion of said shoulder contacts with the inner edge of the inwardly extending flange 10.

25 The flange 26 is provided at intervals with countersunk holes 31 which extend therethrough through which screw-threaded bolts 32 extend. The inner sides of the heads of these bolts are tapered, as indicated at 33, so as to form a tight fit within the countersunk portions of the openings 31. The inner ends of the screw-threaded bolts 32 are in screw-threaded engagement with screw-threaded holes 33 through a 35 clamping member divided into three sections 34 which sections, when placed in end to end position as shown in Fig. 2 of the drawings, correspond to the shape of the flange 9. In the construction as shown this 40 flange and the clamp are circular. The outer edges of these members 34 are situated underneath the inwardly extended flange 10 and the said members are each provided with a forwardly extending flange 35 the 45 forward edge of which is adapted to contact with the inner end of the header 25. By screwing the inner ends of the bolts 32 into the screw-threaded openings 33 through the members 34 the said members and the flange 50 26 may be caused to clamp tightly against the opposite sides of the flange 10. By unscrewing and removing the screw-threaded bolts 32 the header may be readily disconnected from the flange 9, as is clearly apparent. This having been done it also will 55 be apparent that the sections 34 previously referred to may then be removed.

The water or other cooling medium enters the apparatus through a header (not shown) 60 at the opposite end of the casing 1 and flows through the pipes or tubes 5 and escapes from the header 25 through an outlet port or opening at 37, all in known manner.

It will be seen that by my invention I 65 have provided a simple and efficient novel

construction of means whereby a header may be readily detachably secured to the expansion tube-plate or sheet of a heat exchange apparatus and have also provided novel means whereby the joint between the latter and the casing may be more effectively sealed than heretofore has been the case by reason of the fact that the gland 17 may be tightened at will and as desired to effect a tightening and clamping action 70 of the packing material 16 within the recess 15 surrounding the outer edge of the tube-plate or sheet 8 and the flange projecting forward therefrom.

It will also be seen that by my invention 80 I have provided means whereby in case of a leak through the packing around the tube-sheet or between the edge of the flange 9 and the header the leaking liquid will flow to the outside of the apparatus where it 85 can be seen readily so that it can be readily determined through which joint the leakage is taking place so that such joint may be tightened independently of the other joint and without interrupting the service of the 90 apparatus. It will also be noted that by means of the arrangement embodying my invention it is impossible for one of the liquids to leak through a joint and mix with the other liquid. 95

Having thus described my invention what I claim and desire to secure by Letters Patent is:

1. In heat exchange apparatus, the combination of a tube-plate having a forwardly 100 extending flange which terminates at its forward edge in an inwardly extending flange, a header having a flange, the outer edge portion of which is adapted to contact with the forward edge of the first named flange, a 105 clamping member comprising a plurality of sections the outer edges of which are situated underneath the said inwardly extending flange, and means for clamping the latter flange between the said clamping member 110 and the flange on said header.

2. In heat exchange apparatus, the combination of a casing, a plurality of heat exchange tubes situated therein, a tube-plate secured to one end of each of said tubes, the 115 said tube-plate being situated within the said casing adjacent an end thereof, which plate is provided with a forwardly extending flange and the said casing having an end portion which projects beyond the said tube-plate which end portion is provided with a recess upon the inner side surrounding a portion of the edge of said tube-plate and a portion of the said flange, packing material within the said recess, a gland surrounding the first named flange and projecting into the said recess, means for forcing the said gland into the said recess, a header, and means for securing the same to the said flange. 125

3. In heat exchange apparatus, the combination of a casing, a tube-plate situated within said casing adjacent one end thereof, which plate is provided with a forwardly extending flange, a header, means for detachably connecting said header to said flange, and means for hermetically sealing the joint between the said tube-plate and the said casing.
- 10 4. In heat exchange apparatus, the combination of a casing, a tube-plate situated within the said casing and having a flange extending forwardly, a portion of which flange is surrounded by an end portion of said casing, a header, means for detachably connecting said header to said flange, means for hermetically sealing the joint between the said tube-plate and the said casing, and means for hermetically sealing the joint between the said header and the said flange.
- 15 5. In heat exchange apparatus, the combination of a tube-plate having a flange at its edge which extends forwardly and which terminates at its forward edge in an inwardly extending relatively narrow flange, a header having a flange at its inner end which extends at right angles to the tube-plate flange and is adapted to overlie the forward edge thereof, the said header flange being provided with countersunk openings at intervals therein, a clamping member comprising a plurality of sections adapted to be placed end to end, the outer edges of which are situated underneath the second named flange and which sections are provided with screw-threaded openings at intervals which are adapted to be brought into alinement with the openings through the header flange, and bolts having heads the inner sides of which are tapered to fit the countersunk portions of the said openings, which bolts are adapted to engage screw-threaded openings within the said clamping member to effect clamping of the second named flange between the said sections of the clamping member and the header flange.
- 20 6. In heat exchange apparatus, the combination of a casing, a bundle of tubes therein, a tube-plate, the edge of which forms an expansion joint with the adjacent portion of said casing, which tube-plate is secured to the adjacent ends of the tubes of said bundle, a header secured to said tube-plate, and means whereby leakage between the casing and header is prevented.
- 25 7. In heat exchange apparatus, the combination of a casing, a bundle of tubes therein, a tube-plate, the edge of which forms an expansion joint with the adjacent portion of said casing and the said tube-plate being secured to the adjacent ends of the tubes of said bundle, packing material intermediate the outer edge of said tube-plate and the said casing, a header secured to said tube-plate, packing means intermediate said header and said tube-plate, and means whereby the said packings may be tightened independently of each other and without interfering with the operation of the said apparatus.
- 30 In testimony that I claim the foregoing as my invention, I have hereunto signed my name this 21st day of November, A. D. 1922.
- 35

KARL MUHLEISEN.
